UNITED STATES PATENT OFFICE.

FRANK E. TEN EYCK, OF AUBURN, NEW YORK, ASSIGNOR TO AUTO AIR-ROTOR COMPANY, OF CHICAGO, ILLINOIS, A CORPORATION OF MAINE.

COMBINED AIR-PUMP AND STARTER FOR EXPLOSIVE-ENGINES.

1,140,723.

Specification of Letters Patent. Patented May 25, 1915.

Application filed June 12, 1914. Serial No. 844,611.

To all whom it may concern:

Be it known that I, FRANK E. TEN EYCK, a citizen of the United States, residing at Auburn, in the county of Cayuga and State 5 of New York, have invented certain new and useful Improvements in Combined Air-Pumps and Starters for Explosive-Engines; and I do hereby declare the following to be a full, clear, and exact description of the 10 invention, such as will enable others skilled in the art to which it appertains to make and use the same.

My invention consists in the novel features hereinafter described, reference being 15 had to the accompanying drawings which illustrate an embodiment of the invention selected by me for purposes of illustration, and the said invention is fully disclosed in the following description and claims.

20 Referring to the said drawings,

Figure 1 represents a side elevation of my improved air pump and starter showing it operatively connected with the explosion engine of an automobile or other motor 25 vehicle, a portion of the dash board being indicated in section and the location of the air pressure gage and control mechanism for the hand operated control valve being also illustrated. Fig. 2 is a front end elevation 30 of the apparatus shown in Fig. 1. Fig. 3 is a rear end elevation of the combined pump and starter detached, drawn to a slightly enlarged scale. Fig. 4 is a top plan view of the combined pump and starter, a 35 portion of the mechanism being indicated in section. Fig. 5 is a rear end view of a portion of the apparatus showing the main and auxiliary distributor valve casings with the covers removed and the valves removed.

40 Fig. 6 is a detail view of the main distributor valve showing the inner face thereof. Fig. 7 is a similar view of the auxiliary distributor valve showing the inner face. Fig. 8 is a horizontal section on line 8—8 of Fig. 45 3 looking in the direction of the arrows, and showing the assembled relation of the main and auxiliary distributor valves. Fig. 9 is a side elevation partly in section of the hand operated control valve on the dash. 50 Fig. 10 is an elevation with the cover of the 55 valve casing removed, showing the valve in position. Figs. 11 and 12 are detailed views of the inlet and exhaust valves with which each cylinder of the combined pump and starter is provided. Fig. 13 is a detailed

sectional view of one of the automatic valves with which each cylinder of the pump and starter, and each cylinder of the engine, is provided.

The object of my invention is to provide 60 an apparatus operatively connected to and combined with an explosion engine which can be operated by the engine as a pump for the purpose of compressing and storing air or other motor fluid, and which can be operated by said compressed motor fluid so as to convert it into a motor for the purpose of starting the explosion engine, that is to say, for the purpose of turning over the engine sufficiently to enable it to operate as 70 an explosion engine under its own power. While the combined pump and compressed fluid motor herein shown and described may be relied upon to impart sufficient motion 75 and momentum to the moving apparatus of the explosion engine to start the same, in the preferred embodiment of my invention herein shown and described, I prefer to combine with my improved pump and compressed fluid motor, operative means for admitting the compressed motor fluid simultaneously to the engine cylinders and motor cylinders and for automatically controlling the supply of motor fluid so that the engine 80 will be more quickly and powerfully actuated and will more quickly attain the desired momentum to enable it to operate under its own power supplied by the combustion of the explosive mixture. I also prefer to provide means for relieving the engine 85 cylinders in which compression is taking place during the time that the compressed motor fluid is being supplied directly to the engine cylinders in succession, or in other words, for relieving the compression 90 in the next preceding engine cylinder to facilitate the operation of the engine under the force of the compressed motor fluid and enable it to more quickly attain the desired 95 speed and momentum. In this my preferred 100 construction, the combined pump and starter may be made very small and need not be capable of exerting more than the necessary power for turning the engine off of the dead center as in practice it is found 105 that an explosion engine or internal combustion engine has a tendency to stop at the dead center and as will be hereinafter more fully described, as soon as the compressed fluid air has moved the crank shaft 110

of the engine off of the dead center, the compressed motor fluid will be admitted to the appropriate cylinder of the engine, thus enabling it to start immediately under the actuation of the motor fluid and to thereafter quickly and almost instantaneously attain the necessary speed and momentum to operate under its own power. It is to be understood, however, that the combined pump and compressed fluid motor herein described is also capable of actuating and starting an explosion engine by itself without the coöperation of means for supplying compressed motor fluid to the engine cylinders, if desired.

In the accompanying drawings 1 represents the explosion or internal combustion engine, which in this instance is provided with four explosion cylinders 2, 3, 4, and 5.

6 represents the crank shaft which is provided in this instance with a sprocket wheel 7 by means of which power may be transmitted to the combined pump and compressed fluid motor.

The engine as illustrated in Fig. 1 is mounted on the forward part of the chassis of an automobile or other motor vehicle, the dash board of which is indicated at 8.

The combined pump and motor is shown in Figs. 1 and 2 as located at one side of the engine and suitably supported in fixed relation thereto and it comprises a base portion 10 and a plurality of cylinders, three cylinders 11, 12, and 13, being shown in the embodiment illustrated in the drawings. Each of the cylinders is provided with a piston and piston rod of ordinary construction (not shown) operatively connected in the usual manner with a crank shaft 14, which in this instance is provided with a pinion 15 having a broad face, said pinion being in mesh with a gear wheel 16 mounted on a secondary shaft 17, journaled in bearings in the base 10 of the pump, and extending longitudinally through the same, said gear 16 being connected to the shaft by a key 18 and being capable of sliding longitudinally on the shaft. Loosely mounted on the shaft is a hub or clutch member 19 provided with a clutch recess 20 to receive a clutch projection 21 which is preferably secured to the gear 16 and upon the hub or clutch member 19 is secured a sprocket 22 by means of a key or otherwise, which sprocket is connected by a sprocket chain 9 with the sprocket 7 on the crank shaft of the engine. I also provide automatic means for clutching the sprocket wheel 22 to the secondary shaft 17, in this instance by moving the gear wheel 16 endwise on the shaft 17 to interlock the clutch projection 21 and recess 20 (see Fig. 4) which mechanism includes a cylinder 23 provided with a piston 24 working therein, and piston rod 25 having a shoulder 26 for limiting its outward motion by engagement

with the outer end of the cylinder, the said piston rod being provided with a yoke 27, engaging an annular groove on the hub of the gear wheel 16, and a retracting spring 28 being provided in this instance within the cylinder 23 and surrounding the piston rod 25 for returning the parts to normal position.

Each of the pump cylinders is provided with an inlet valve 30, one of which is shown in detail in Fig. 11, in this instance provided with a spring seated valve, and the upper end of the pump cylinders, which are preferably formed as a single casting, are connected by a delivery passage 31, indicated in Fig. 12, and each engine cylinder is provided with an outlet valve indicated at 32 in Fig. 12, provided with spring pressed ball valve which opens to permit the air compressed in the cylinder to pass through the discharge passage 31. The discharge passage 31 communicates with a pipe 33 which is connected through the hand operated control valve hereinafter referred to with a storage tank (not shown) and I prefer to designate the pipe 33 as the pump line, for convenience of reference.

34 represents a branch line or by pass from the pump line or discharge passage 31 to the clutch operating cylinder 23 (see Fig. 4), for supplying compressed air to the cylinder 23 to operate the clutch. From the foregoing description of the apparatus, it will be apparent that if the tank is partially charged with air and the control valve hereinafter described is placed in such a position as to open communication between the pump line 33 and the tank, the back pressure from the tank will pass to the by pass 34 and actuate the piston 24, thus clutching the gear 16 to the engine driven sprocket 22 and if the engine is running, the pump will be immediately actuated to compress air and force it back into the tank until the desired pressure is obtained, when the pump line 33 will be cut off from the tank and the spring 28 will automatically disconnect the pump from the engine.

Each of the pump cylinders is provided with an automatic pressure operated valve 35, one of which is shown in detail in Fig. 13. This valve comprises a body 36, provided with a valve seat 37, a needle valve or stem valve 38, adapted to slide in a suitable guiding means provided in connection with the casing 36, in this instance a threaded sleeve 39, the valve stem being provided with a piston 40 working in an extension chamber 41 and provided with a spring 42, which normally holds the valve seated. The casing 36 is provided with an inlet aperture 43 to which a pipe may be connected, and the extension chamber is provided below the piston with an inlet 44 to which a pipe can be connected, for the purpose of introducing

compressed air to operate on the lower face of the piston 40 and raise the valve off of its seat. The relief chambers 45 below the pistons 40 in all of the automatic valves 35 are connected with a by pass 46 in any desired way, in this instance by connecting pipes 46^a (see Fig. 4), so that the pistons 40 may be simultaneously actuated by compressed air entering through the pipe or by pass 46 as hereinbefore explained.

At one end of the pump mechanism I provide what I term the main distributor casing, indicated at 50 and best shown in Figs. 5 and 8. This casing is conveniently formed 15 on the end of the pump base and a reduced portion 14^a of the pump crank shaft extends into it and is provided at its end with a pair of apertures 14^b. The casing 50 is closed by a cap 51 and within the casing is a rotary disk valve 52, which is preferably provided with pins 53 for engaging the apertures 14^b in the crank shaft and connecting the disk to the crank shaft. The inner face of the disk is ground to fit against the inner face of the recess formed within the casing 50 and the disk is provided with a segmental slot 54 and with a segmental recess 55 on its inner face having a short passage 56 extending therefrom and communicating 25 with a central passage 14^c in the crank shaft 14, which terminates at one side of the shaft at some convenient point inside of the casing to take care of the exhaust when the pump is used as a fluid pressure motor as herein- 30 after described. It will be understood that the casing 10 of the pump will be provided with the usual breathing aperture 10^a. The bottom face of the recess within the casing 50, against which the valve disk 52 rotates is 35 provided with three ports 11^a, 12^a, and 13^a, from which passages extend which are connected by pipes 11^b, 12^b, and 13^b, respectively with the casing 36 of the automatic valve on the pump cylinders 11, 12, and 13 40 respectively. The relation of the segmental aperture 54 and the segmental recess 55 of the valve disk 52 are such that during the rotation of the disk compressed motive fluid will be admitted to the pump cylinders 11, 45 12, 13, in rotation, to actuate the same through the aperture 54 while the cylinders will be permitted to exhaust the expanded motor fluid which returns through the same pipes, through the recess 55, to the exhaust 50 aperture 14^c in the shaft or the exhaust might be delivered in any other desired manner to the atmosphere. The interior 55 of the casing 50 communicates with a lateral passage 57 in a boss 58 on the end of the pump casing, which boss is provided with an inlet aperture 59 connected by a pipe 60 with the compressed air tank through the hand operated control valve hereinafter described, the pipe 60 being 60 termed for convenience, the starter pipe line.

The boss 58 is also provided with a lateral aperture 61 to which is connected the by pass pipe 46 before referred to, which communicates with the relief chambers of all the automatic valves 35 for the purpose of 70 lifting the valves off their seats, as before stated.

It will now be seen that if the connection between the pump line 33 and the tank is cut off, and communication between the 75 starter pipe line 60 and the tank is established, compressed air from the tank at high pressure will be delivered through the starter pipe line to the boss 58 and will pass thence through the pipe 46 to the relief 80 chambers of the several automatic valves, thus opening the valves 38 and the motor fluid will also pass through the passage 57 into the main distributor 50 and through the slot 54 and the particular port which is uncovered at the time to one of the pump cylinders through the automatic valve 35 thereof, thereby imparting motion to the piston in the said valve, and starting the pump mechanism, which then acts as a motor. 90 The rotation of the disk 52 will distribute the compressed fluid to the pump cylinders in rotation as before stated, and the cylinders will exhaust in the manner described so that a rapid rotation of the shaft 14 is 95 effected by the device acting as a motor. The introduction of compressed air into the pump cylinders will simultaneously open the outlet valves 32 thereof and permit a portion of the compressed fluid to pass into the 100 passage 31, which being in communication with the by pass 34 and the trunk line 33 being closed as before stated, will effect automatically the operation of the piston 24 in the cylinder 23 and clutch the wheel 16 105 to the sprocket wheel 22 connected with the engine, thereby imparting motion from the crank shaft of the starter to the engine shaft as will be readily understood.

As before stated in the preferred form 110 of my invention herein shown, I also provide means for simultaneously admitting the pressure fluid when the pump mechanism is operated as a motor, to the successive cylinders of the explosion engine and for this purpose I employ an auxiliary distributor which is driven by the starter and is arranged so as to be connected to the engine shaft at proper timing therewith. In the embodiment of my invention herein shown, 115 I operate the auxiliary distributor by means of the secondary shaft 17 before referred to and the distributor casing 65 is preferably formed on the end plate of the pump base 10 adjacent to the main distributor casing 50 120 and is in communication with the passage 57 receiving compressed air from the starter pipe line 60 as clearly shown in Figs. 5 and 8. The casing 65 is provided with a removable cap 66 and contains a rotary disk valve 125 130

67 which is provided with pins 68 engaging apertures in the end of a reduced portion 17^a of the shaft 17 and the said shaft 17 is provided with a relief passage 17^c extending longitudinally therethrough and discharging at one side of the shaft, preferably within the pump base. The disk valve 67 is provided with a segmental recess 69 for admitting the motor fluid successively to 10 ports 2^a, 3^a, 4^a, and 5^a, which communicate with passages leading to pipes 2^b, 3^b, 4^b, and 5^b, the said pipes extending respectively to automatic valves 35^a, mounted on and communicating with the several cylinders of the 15 engine. These automatic valves 35^a are constructed like the automatic valves 35, one of which is shown in Fig. 13 in detail, except that they are slightly larger, and it will be unnecessary to repeat the description of the 20 valve 35. Each of these valves 35^a is provided with a relief chamber, the relief chambers being connected by pipes 46^b which are preferably slightly curved to avoid interference with the spark plugs of the 25 explosion engine cylinders, and the last valve 35^a of the series is connected by a short by pass 46^c (see Fig. 1) with the starter pipe line 60 so that pressure fluid from the starter pipe line can pass to the relief chambers of all 30 the valves 35^a beneath the pistons therein, and lift the valves off of their seats, leaving the automatic valves in open communication with the auxiliary distributor ports 2^a, etc., before referred to, and thus enabling 35 the distributor valve disk 67 to supply compressed air to the engine cylinders in rotation.

In starting an explosion-engine the power exerted to turn over the engine shaft is 40 naturally resisted by the compression in the particular cylinder the piston of which is moved backward toward the head of the cylinder, and to facilitate the quick starting of the engine, I prefer to relieve this compression automatically, which occurs in one of the cylinders, in advance of the one to which compressed motor fluid is being admitted in the cycle of operation of the engine. To this end the valve disk 67 is provided in its 45 inner face with a segmental recess 70 (see Fig. 7) in communication with the central passage 17^c of the shaft 17, and this recess 70 is located a sufficient distance in advance of the recess 69 to bring it into communication with the port for the next preceding cylinder, or in other words, the cylinder in which compression is taking place, at the 50 time the recess 69 opens one of the ports of the auxiliary distributor to receive compressed motor fluid. This permits the compression in the cylinder ahead to be relieved back through the auxiliary distributor 55 35 and through the passage 17^c. In order to facilitate the operation of the engine under 60 its own explosive power, I prefer to make 65

this relief passage as small as possible so that it will have the necessary effect while when the engine attains high speed, the minute passage will not be sufficient to permit all of the compressed explosive mixture 70 which will be drawn into the engine cylinders and compressed therein to be relieved in the short instant of time that the recess 70 is over the appropriate port. To this end I conveniently insert in the relief passage 75 17^c a bushing 17^d provided with a very minute central aperture as shown in Fig. 8 which restricts the relief passage and accomplishes the desired result before stated. Obviously, the compressed air employed in operating the cylinders of the engine in starting will exhaust through the normal exhaust ports of the engine when the exhaust valves of the engine are opened by the cam mechanism forming part of the engine mechanism, the details of which are thoroughly understood by those skilled in the art and need not therefore be particularly described and shown herein.

For convenience in applying my invention 90 to the engines of automobiles and other motor vehicles so that the mechanism can be controlled from a point adjacent to the steering wheel or steering shaft, I employ a controlling valve which is illustrated in detail 95 in Figs. 9 and 10, and which is also shown in Fig. 1. This control valve comprises a valve casing 75 which may be conveniently mounted upon the steering sleeve 76 through which the steering shaft 77 provided with 100 the usual steering wheel 78, extends. This casing is provided on the rear face with a removable cover 75^a preferably provided with a hollow boss 75^b which is connected at one end with a pipe 80 extending to the 105 tank (not shown), which may be of any desired form or size and which is preferably provided with the usual cut off valve by which it can be hermetically closed, so as to disconnect it from the pipe line and prevent 110 leakage when the apparatus is left for a considerable time in order that there always may be a reserve of compressed fluid in the tank. The other end of the passage in the boss 75^b is connected by a pipe 81 with a 115 pressure gage 82, which preferably has its dial so located that it can be seen by the operator. The valve casing 75 is provided on its interior face with two ports 83 and 84 120 communicating with lateral passages which are connected respectively with the starter pipe line 60 and the pump line 33. As previously stated, a by pass 46^c is connected to the starter pipe line and this connection may be accomplished conveniently by means of a secondary passage in the valve casing, indicated at 46^d communicating with the port 83 and to which the pipe 46^c is connected, or the pipe 46^c might be directly 125 connected with the starter pipe line 60 at 130

some other point, if it is found more convenient. The valve casing 75 is also provided with oscillating disk valve 90 which is provided with two apertures 91 and 92 adapted the one to be brought into registration with the port 83 and the other to be brought into registration with the port 84, and the disk valve is provided with lateral projections 93 at opposite sides, adapted to engage a pin 94 and stop the valve when it is in one or the other of its operative positions, while in a central position between the two operative positions, both of the ports 83 and 84 will be closed by the solid portion 10 of the disk as clearly shown in Fig. 10. For convenience the oscillating valve disk 90 is provided with a valve stem 95 extending out through the front of the casing and provided with an operating handle 96 and pointer 97 which is placed over the dial 98, and the dial will be marked with an indication for "off" or neutral position and also for the "pump" and "starter" positions. The control valve may be provided with a 20 suitable clamp as indicated at 75^a for attaching it to the sleeve 76 of the steering head and the shaft 95 may also be supported at its outer end in a suitable bearing 99 provided with a clamp 100 for engaging the 30 steering head and holding the shaft in proper position. I also prefer to employ a spring indicated at 100 in Fig. 9 for maintaining the oscillating disk 90 in close engagement with the inner face of the valve 35 casing 75.

The various parts of the apparatus having now been described, it will be understood that if the engine is running and it is desired to compress a quantity of air into the 40 tank and store the same, the operator will throw the handle 96 to the indicated position for operating the combined pump and starter as a pump, which moves the control valve disk 90 into position to bring the aperture 92 into communication with the port 84, the back pressure of air already contained in the tank will immediately exert itself through the pump line 33 as before described and through the by pass 34 so as to 45 actuate the piston 24 and connect the gear 16 with the sprocket 22, thereby transmitting power from the engine to the pump shaft 15 and driving the pistons thereof so as to compress air therein, which is discharged through the outlet valves 32, the 50 passage 31 communicating therewith, and back through the pump line 33, ports 84 and 92 and tank pipe 80, to the tank, the accumulated pressure being indicated on the 55 gage 82. When the gage reaches the desired point say 200 lbs., the operator will move the handle 96 to the neutral position, thus shutting the pump line at the control valve and the loss of pressure in the pump 60 line which follows will permit the spring 65

28 to disconnect the clutch mechanism 21-20 and disconnect the pump from the engine. Supposing that the engine is at rest and it is desired to start the engine, the operator will move the handle 96 into the 70 position to bring the valve port 91 into registration with the port 83 and establish communication between the tank and the starter pipe line 60, and simultaneously establish communication between the tank 75 and by pass 46^a leading to the automatic valves 35^a of the engine cylinder, and simultaneously establishing communication between the tank and by pass 46 leading to the relief chambers of the automatic valves 80 35 of the pump cylinders. The compressed air from the tank passing through the starter pipe line 60 passes to the boss 58 and to the main and auxiliary distributor before described. As the engine usually stops 85 on dead center the admission of compressed air to the appropriate port in the auxiliary distributor to the appropriate engine cylinder through the automatic valve 35^a, the valve of which is now open, would not effect 90 the movement of the piston therein, but the admission of the compressed air through the main distributor to the appropriate pump cylinder, will immediately start the pump, which acts as a motor, and the admission of compressed air to any pump cylinder transmits the pressure of the motor 95 fluid as before stated through the exhaust valves 32 of the pump and the passage 31 to the by pass 34 and cylinder 23, causing 100 the piston 24 to act and again connect the gear wheel 16 with the engine. This enables the pump mechanism acting as a starter to move the engine shaft off the dead center and instantly the piston in the cylinder 105 which is in communication with the auxiliary distributor, will respond and start the engine, while the pump mechanism, acting as a motor continues to assist the engine cylinders. It will also be understood that 110 the engine cylinder preceding the one which receives compressed air, is partially relieved of its compression, as before stated, to facilitate the turning over of the engine. By this means the engine is brought practically 115 by one or two revolutions of the crank shaft to high speed, and as the cylinders not immediately operating under compressed air are drawing and partially compressing their charges of explosive material which will be 120 exploded by the igniters in the usual manner, the effect is an almost instantaneous starting of the engine under its own power, after which the handle 96 is thrown to the 125 neutral position and the supply of compressed fluid to the pump and engine cylinders is cut off, after which the engine continues to operate under its own power and the spring 28 withdraws the clutch member 130 21 from the recess 20, permitting the com-

bined pump and starter to be brought to a condition of rest.

In order to quickly relieve the pressure in the pump line 33 whenever the control valve is moved to neutral position, so as to permit the spring 28 to retract the piston 24 and withdraw the clutch member 21, I prefer to provide the control valve with special means for relieving the pressure in the pump line, which consists in this instance of the following instrumentalities. The valve casing of the control valve is provided with a small relief passage 75° extending from the bearing aperture of the valve shaft 95 to the atmosphere. The valve shaft is provided with a recess 95^a adapted to be brought into registration with the relief passage 75° when the valve 90 is in neutral position and the valve 90 is provided with a recess 90^a in its face, communicating with the shaft recess 95^a and extending outwardly far enough so that when the valve is in neutral position, this recess 90^a will extend over the port 84, which communicates with the pump pipe line 33. The result of this construction is that as soon as the valve 90 is turned to neutral position from either the pump position or starter position, it will establish communication between the pump pipe line 33 and the atmosphere through the valve recess 90^a, shaft recess 95^a, and relief passage 75°, thus permitting the pump line to immediately relieve its pressure, thereby relieving the pressure in the cylinder 23 behind the piston 24, and permit the spring 28 to quickly withdraw the clutch member 21.

When the control valve is in neutral position and the relief passage 75° in communication with the port 84, the reduction of pressure in the pump line 33 just described, permits the compressed fluid in the particular cylinder of the pump and starter which at the moment is in communication with the main distributor 51 (and one or other of said cylinders is at all times in communication with the distributor), to exhaust through the exhaust valve into the pump line 33 and thence to the atmosphere through the relief passage 75°. This relieves the compression in the starter line 60 extending to the distributor 51 and in the by pass 46 communicating with the actuating cylinders of the auxiliary inlet valves 35 of the pump and starter, thus permitting the said valves to close. At the same time the pressure in the by pass 46° extending from the starter pipe line 60 to the actuating cylinders for the auxiliary valves 35^a of the engine cylinders, is also reduced, thus permitting said valves to close and quickly restore the entire apparatus to its normal position as soon as the controlling valve is restored to neutral position.

When the combined pump and starter is operated from the engine as before de-

scribed to compress air into the tank if the operator should neglect to disconnect the pump, by throwing the controlling valve to neutral position when the desired pressure, say two hundred pounds (200 lbs.) is 70 reached in the tank, the springs holding the automatic valve 35 on their seats, which are adjusted to resist any pressure below that desired in the tank, will thereafter yield and permit an escape of compressed 75 air from the pump cylinders. The valves 35 will thus act as safety valves to prevent the accumulation of too great pressure in the tank.

As before stated, I prefer to provide the 80 herein described means for admitting compressed air to the cylinders of the engine itself, as a quicker starting of the engine is obtained, since power is applied directly to the pistons of the engine and the combined 85 pump and starter mechanism merely acts under these conditions to turn the engine off the dead center and assist the operation of the engine in attaining high speed quickly. I wish it to be understood that my 90 improved pump and starter mechanism can be used without this direct connection with the engine cylinders by omitting the auxiliary distributing mechanism hereinbefore described and the connections therefrom to 95 the cylinders, and the automatic valves 35^a will also be omitted from the engine cylinder under such conditions. The apparatus so modified can be utilized to compress air as before described, and also to act as a 100 motor and start the engine through the connection between the gear wheel 16 and the sprocket wheel 22 and sprocket chain 9.

The convertible motor compressor above referred to is not herein specifically claimed, 105 as it forms the subject matter of a separate application.

What I claim and desire to secure by Letters Patent is:—

1. In starting mechanism for an explosive engine, the combination with a compressed fluid motor, means for supplying compressed fluid thereto, means for operatively connecting the motor with the crank shaft of the engine, connections from 110 the means for supplying compressed fluid to the motor, extending directly to a cylinder of the engine, independent of any supply of explosive mixture thereto for positively operating the engine by fluid pressure.

2. In starting mechanism for an explosive engine, the combination with a compressed fluid motor, a storage tank, means for supplying compressed fluid from said tank to said motor, means for operatively connecting the motor with the crank shaft of the engine, and means operatively controlled by the operation of the motor for supplying compressed fluid from the tank 130

directly to a cylinder of the engine, independently of the supply of the explosive mixture thereto, whereby said motor will operate to rotate the engine shaft and will 5 also supply the said engine cylinder with compressed fluid acting directly therein.

3. The combination with an explosion engine provided with a plurality of cylinders, of a compressed fluid motor, means 10 for operatively connecting the same with the engine crank shaft, a storage tank connected with the motor, a distributor operatively controlled by the motor, connections from the said distributor to the cylinders of 15 the engine independent of any means for supplying explosive mixture thereto for positively operating the engine by fluid pressure, and a connection from the storage tank to said distributor.

20 4. The combination with an explosion engine provided with a plurality of cylinders, each of said cylinders having an auxiliary inlet for compressed fluid, of a combined pump and motor, means for operatively connecting the same with the crank shaft of 25 the engine, a storage tank connected with the said pump and motor, a distributor operatively controlled by said pump and motor, connections from said distributor to 30 the auxiliary air inlets of the engine cylinder, a connection from the tank to said distributor, normally closed valves for closing said inlets, and means for automatically opening said valves.

35 5. The combination with an explosion engine provided with a plurality of cylinders, each of said cylinders having an auxiliary inlet for compressed fluid; of a combined pump and motor, means for operatively connecting the same with the crank shaft of 40 the engine, a storage tank connected with said pump and motor, a distributor operatively controlled by said pump and motor, connections from said distributor to the 45 auxiliary air inlets of the engine cylinder, a connection from the tank to said distributor, normally closed valves for closing said inlets, a cylinder and piston for opening each of said valves, and a by pass for 50 connecting the tank with said valve-controlling cylinders for automatically opening said valves.

6. The combination with an explosion engine provided with a plurality of cylinders, 55 each of said cylinders having an auxiliary inlet for compressed fluid, of a combined pump and motor, means for operatively connecting the same with the crank shaft of the engine, a storage tank connected with 60 said pump and motor, a distributor operatively controlled by said pump and motor, connections from said distributor to the auxiliary air inlets of the engine cylinder, said distributor including among its mem-

bers a distributor valve provided with 65 means for establishing communication between the tank and the engine cylinders successively, said valve being also provided with means for establishing communication between said engine cylinders and the atmosphere to relieve compression in the cylinders and facilitate their operation under compressed fluid.

7. The combination with an explosion engine having a plurality of cylinders, each 70 having an auxiliary inlet for compressed motor fluid, of a combined pump and motor, means for operatively connecting the same to the crank shaft of the engine, a storage tank connected with said combined pump 80 and motor, a distributor comprising a valve casing having ports connected with the auxiliary inlets of said engine cylinders, and having a relief passage communicating with the atmosphere, and a rotary distributor 85 valve in said casing operatively connected with the combined pump and motor and provided with an inlet port adapted to establish communication between the storage tank and the engine cylinders in succession, 90 said valve having a relief aperture adapted to establish communication between the engine cylinders and said relief passage.

8. The combination with an explosion engine having a plurality of cylinders, each 95 having an auxiliary inlet for compressed motor fluid, of a combined pump and motor, means for operatively connecting the same to the crank shaft of the engine, a storage tank connected with said combined 100 pump and motor, a distributor comprising a valve casing having ports connected with the auxiliary inlets of said engine cylinders and having a relief passage communicating with the atmosphere, and a rotary distributor valve in said casing operatively connected with the combined pump and motor and provided with an inlet port adapted to establish communication between the storage tank and the engine cylinders in succession, 105 said valve having a relief aperture adapted to establish communication between the engine cylinders and said relief passage, said relief passage being of such reduced size as to be insufficient to entirely 110 relieve the compression in the cylinders when the engine is being operated at high speed.

9. The combination with an explosion engine provided with a plurality of cylinders, 115 each of said cylinders having an auxiliary inlet aperture, a normally closed valve controlling said aperture, and a piston and cylinder for opening said valve, of a combined pump and motor, a storage tank connected therewith, a main distributor interposed between the tank and the cylinders of the pump and motor for supplying com-

- pressed fluid to operate the same as a motor, an auxiliary distributor operatively connected with the pump and motor, connections between said auxiliary distributor 5 and the auxiliary inlet apertures of the engine cylinders, and connections between said storage tank and the valve controlling cylinders of the engine cylinders for opening said valves.
- 10 10. The combination with an explosion engine having each cylinder provided with an auxiliary inlet, of a combined pump and motor having each cylinder provided with an auxiliary inlet, a storage tank connected with said pump and motor, a main distributor operatively connected with the pump and motor, connections from said distributor to the auxiliary inlets of the pump cylinders for operating the mechanism as 15 a motor, an auxiliary distributor operatively connected with the pump and motor, connections between said auxiliary distributor and the auxiliary inlets of the engine cylinders, a connection from the tank 20 to both of said distributors, clutch mechanism for operatively connecting the combined pump and motor to the crank shaft of the engine, a cylinder and piston for throwing said clutch into operative position, and a by pass for establishing communication between the air tank and said cylinder for automatically operating said clutch when the combined pump and motor 25 is operated for either purpose.
- 30 35. 11. The combination with an explosion engine having each cylinder provided with an auxiliary inlet, a normally closed valve for said inlet, and a cylinder and piston for opening each of said valves, of a combined 40 pump and motor having each cylinder provided with inlet and outlet valves and with an auxiliary inlet aperture, a normally closed valve controlling said aperture and a cylinder and piston for opening each of 45 said valves, a storage tank connected with the outlet valves, a main distributor operated by the pump and motor, connections between the distributor and the auxiliary inlet apertures of the pump and motor, a 50 by pass for connecting the storage tank with said cylinders for controlling the valves for the auxiliary inlets of the pump and motor, an auxiliary distributor operatively connected with the pump and motor, connections between said distributor and the auxiliary inlets of the engine cylinders, means for supplying compressed fluid from 55 the storage tank to each of said distributors, a by pass for connecting the storage tank 60 with the cylinders controlling the valves for the auxiliary inlets of the engine cylinders, clutch mechanism for connecting the pump and motor with the engine crank shaft, a cylinder and piston for automatically op- erating said clutch when the pump and motor 65 is operated for either purpose, and a by pass for establishing communication between said cylinder and the storage tank.
12. The combination with an explosion engine having each cylinder provided with an auxiliary inlet, a normally closed valve controlling said inlet, and a cylinder and piston for opening said valve, of a combined pump and motor having each cylinder provided with an inlet and outlet valve, 70 an auxiliary inlet, normally closed valve therefor, and a cylinder and piston for opening said valve, a storage tank, a pump line connecting the said outlet valves with the storage tank, a main distributor casing provided with an exhaust port and with inlet ports, each connected to one of said auxiliary inlets of the pump and motor cylinders, a rotary distributor valve operatively connected with the crank shaft of the pump and motor for controlling the said inlet and exhaust ports, a starter pipe line connecting the tank with said distributor, a by pass connecting said starter pipe line with the pistons controlling the auxiliary inlet valves of the pump and motor, an auxiliary distributor casing provided with a relief aperture and inlet ports, a connection from each of said ports of one of the auxiliary inlets of the engine cylinder, a rotary distributor valve in said casing operatively connected with the crank shaft of the pump and motor and provided with apertures co-operating with said ports and relief aperture, said distributor casing being connected with the starter pipe line, a by pass from the starter pipe line to the pistons controlling the valves for the auxiliary inlets of the engine cylinders, a controlling valve interposed between the pump line and starter pipe line and said tank, and means for connecting the crank shaft of the pump and motor with the engine crank shaft. 90
13. The combination with an explosion engine having each cylinder provided with an auxiliary inlet, a normally closed valve controlling said inlet, and a cylinder and piston for opening said valve, of a combined pump and motor having each cylinder provided with an inlet and outlet valve, an auxiliary inlet, normally closed valve therefor, and a cylinder and piston for opening said valve, a storage tank, a pump line connecting the said outlet valves with the storage tank, a main distributor casing provided with an exhaust port and with inlet ports, each connected to one of said auxiliary inlets of the pump and motor cylinders, a rotary distributor valve operatively connected with the crank shaft of the pump and motor for controlling the said inlet and exhaust ports, a starter pipe line connect- 100 105 110 115 120 125

ing the tank with said distributor, a by pass connecting said starter pipe line with the pistons controlling the auxiliary inlet valves of the pump and motor, an auxiliary distributor casing provided with a relief aperture and inlet ports, a connection from each of said ports to one of the auxiliary inlets of the engine cylinder, a rotary distributor valve in said casing operatively connected with the crank shaft of the pump and motor provided with apertures coöperating with said ports and relief aperture, said distributor casing being connected with the starter pipe line, a by pass from the starter pipe line to the pistons controlling the valves for the auxiliary inlets of the engine cylinders, a controlling valve interposed between the pump line and starter pipe line and said tank, a clutch for connecting the crank shaft of the pump and motor with the engine crank shaft, a cylinder and piston for throwing said clutch into operative position, and a by pass from the pump pipe line to said cylinder for automatically operating the clutch by back pressure from the tank whether the device is used as a pump or a motor.

14. The combination with an explosion engine having a cylinder provided with an auxiliary inlet, a normally closed valve for said inlet, and a cylinder and piston for opening said auxiliary inlet valve, of a combined pump and motor having a cylinder provided with inlet and outlet valves, and with an auxiliary inlet aperture, a storage tank connected with the outlet valve, a main distributor operated by the pump and motor, connections between the distributor and the auxiliary inlet aperture of the pump and motor cylinder, an auxiliary distributor operatively connected with the pump and motor, a connection between the auxiliary distributor and the auxiliary inlet of the engine cylinder, connections between the tank and said distributors, a by pass for connecting the storage tank with the cylinder controlling the auxiliary inlet valve for the engine cylinder, means for operatively connecting the pump and motor with the engine crank shaft, and a controlling valve interposed in the connections between the tank and the distributor and the said by pass and provided with a relief port adapted to establish communication between said by pass and the atmosphere when the valve is in inoperative position, to quickly relieve pressure in the cylinder controlling the auxiliary inlet valve for the engine cylinder.

15. The combination with an explosion engine having a cylinder provided with an auxiliary inlet, a normally closed valve for said inlet, and a cylinder and piston for opening said valve, of a combined pump and

motor having a cylinder provided with inlet and outlet valves, and with an auxiliary inlet aperture, a storage tank connected with the outlet valve, a main distributor operated by the pump and motor, connections between the distributor and the auxiliary inlet aperture of the pump and motor cylinder, an auxiliary distributor operatively connected with the pump and motor, a connection between said distributor and the auxiliary inlet of the engine cylinder, connections between the tank and said distributors, a by pass for connecting the tank with the cylinder controlling the valve for the auxiliary inlet of the engine cylinder, clutch mechanism for connecting the pump and motor with the engine crank shaft, a cylinder and piston for automatically operating said clutch, a by pass for establishing communication between said cylinder and the storage tank, and a controlling valve interposed in the connections between the tank and the said distributor and said by passes, said valve being provided with a relief port adapted to establish communication between said by passes and the atmosphere when the valve is in inoperative position to quickly relieve pressure in the cylinders for operating the clutch mechanism and the controlling valve for the auxiliary air inlet of the engine cylinder.

16. The combination with an explosion engine having a cylinder provided with an auxiliary inlet, a normally closed valve for said inlet, and a cylinder and piston for opening said valve, of a combined pump and motor having a cylinder provided with inlet and outlet valves, and with an auxiliary inlet aperture, a normally closed valve controlling said aperture, and a cylinder and piston for opening said valve, a storage tank connected with the outlet valve, a main distributor operated by the pump and motor, connections between the distributor and the auxiliary inlet aperture of the pump and motor cylinder, a by pass for connecting the storage tank with said cylinder for controlling the auxiliary inlet valve of the pump and motor, an auxiliary distributor operatively connected with the pump and motor, connections between said distributor and the auxiliary inlet valve of the engine cylinder, connections for supplying compressed fluid from the storage tank to each of said distributors, a by pass for connecting the storage tank with the cylinder controlling the auxiliary inlet valve for the engine cylinder, clutch mechanism for connecting the pump and motor with the engine crank shaft, a cylinder and piston for automatically operating said clutch, a by pass for establishing communication between said cylinder and the storage tank, and a controlling valve interposed in said connections.

between the storage tank and the distributors and said by passes and provided with a relief port adapted to establish communication between the atmosphere and the by passes for relieving pressure in the cylinders controlling the auxiliary inlet valves of the pump and motor and of the engine cylinder and the cylinder for operating the clutch, for quickly relieving pressure there-

in, when the controlling valve is in inoperative position.

In testimony whereof I affix my signature in the presence of two witnesses.

FRANK E. TEN EYCK.
